GREASE DISPENSING PUMP

Walter D. Lynch, Ayrshire, Iowa

Application March 1, 1944, Serial No. 524,616

2 Claims. (Cl. 222—117)

This invention relates to improvements in grease dispensing pumps, and the primary object of the present invention is to provide an improved pump of the above kind by means of which grease may be dispensed from a grease drum into the casing or cylinder of a grease gun for filling the latter in an efficient and expeditious manner without contacting or spilling the grease, and without leaving air pockets in the grease gun after it is filled.

A more specific object of the present invention is to provide a dispensing pump of the above kind which is comparatively simple in construction, highly efficient in operation, and otherwise well adapted to meet with the requirements for successful commercial use.

The present invention consists in the novel form, combination and arrangement of parts hereinafter more fully described, shown in the accompanying drawings, and claimed.

In the drawings, wherein like reference characters indicate corresponding parts throughout the several views:

Figure 1 is a view, partly in side elevation and partly in section, showing a grease dispensing pump constructed in accordance with the present invention and illustrating its use in filling the casing or cylinder of a grease gun.

Figure 2 is an enlarged central vertical section taken on line 2—2 of Figure 1.

Figure 3 is an enlarged transverse section taken on line 3—3 of Figure 1.

Figure 4 is a fragmentary vertical section drawn on an enlarged scale to more clearly reveal details of construction of the pump piston, and showing the valve of the piston closed.

Figure 5 is a view similar to Figure 4 showing the valve of the piston open.

Figure 6 is an enlarged section taken on line 6—6 of Figure 2.

Figure 7 is an enlarged fragmentary section through the filler head of the pump, taken on the plane of line 7—7 of Figure 1.

Referring in detail to the drawings, the present pump is of the lift type and includes a vertical elongated cylinder 5 provided at the top with a removable cap 6, and at the bottom with numerous inlet openings 7. Reciprocable in the cylinder 5 is a piston including a head 8 on the lower end of a piston rod 9 which has an enlarged upper end portion 10 formed at one side with transverse rack teeth 11. Journaled transversely of and extending through the cylinder 5 is a shaft 12 formed with gear teeth 13 that mesh with the rack teeth 11. As shown in Figure 3, 55

the cylinder 5 is formed with a transverse housing 14 in which the shaft 12 is rotatably fitted, and said shaft 12 is provided at one end with a reduced extension 15 that projects through an end of the housing 14 and has an operating crank 16 fixed on the outer end thereof. Fixed to and movable with the piston rod 9 are vertically spaced, apertured discs 17 that slidably fit in the cylinder 5 and guide the piston rod 9 in its reciprocating movements so that said rod is maintained axially of the cylinder.

The piston head 8 includes a cup packing 18 whose body portion is clamped between discs 19 and 20 that are centrally secured, as at 21, to the lower end of the piston rod 9, said discs 19 and 20 and the body of packing 18 being provided with registered openings, as at 22. The packing 18 is arranged to be expanded into engagement with the cylinder 5 on upward movement of the piston and to offer no resistance to downward movement of the piston other than the slight friction between these parts when assembled. Slidable on the piston rod 9 is a valve disc 23 that normally gravitates to a lowered position upon the upper disc 20 to normally close the openings in the piston head at 22. The rod 9 has a suitable stop, such as a cross pin 24, to limit the upward movement of valve disc 23.

Fixed to the cap 6 and communicating through the latter with the interior of cylinder 5 is a discharge spout 25 having a downwardly and outwardly inclined outer end portion 26 on the free extremity of which is provided a piston head 27 adapted to be snugly received within the cylinder 28 of a conventional grease gun, as shown in Figure 1. The piston head 27 consists of a cup packing 29 whose body portion is clamped between clamping plates 30 and 31 threaded on the outer end of the discharge spout 26, a jamb nut 32 being threaded against the inner plate 30 to lock the assembly together. The outer plate 31 is relatively thick and provided with a bore therethrough which communicates with openings through the body of packing 20 and plate 30, and arranged in this bore is a spring-seated check valve 33 that seats in an outward direction. As shown, the spout 26 preferably includes a detachable outer section carrying the head 27. Also, the outlet end of spout 26 is normally closed by a valve member 34 yieldingly seated by a tension spring 35 attached at one end to said valve and at its other end to a transverse pin fixed in and extending across the spout 26, as shown in Figure 7.

In operation, the pump is disposed with its

lower end portion projecting through an opening in the top of a grease drum indicated by dotted lines at D, the upper end of the cylinder 5 projecting above the drum and the lower end thereof resting upon the bottom of the drum as illustrated. The pump may be suitably secured and braced in this position by means generally indicated at 31. The grease, which is in a fluid state, enters the pump cylinder 5 through the apertures 7, and upon rotating the shaft 12 to lower the piston head 8, the grease flows through the piston head 8 and forces the valve 23 open. Thus, the grease passes through the openings at 22 and fills the cylinder 5 above the piston head 8. The shaft 12 is then turned in the opposite direction so as to elevate the piston head 8 and force the grease above the latter out of the upper end of cylinder 5 and through the discharge spout 26, the pressure of the discharged grease causing the valve 34 to open. As the grease is forced into the cylinder 28 of the grease gun, said cylinder is gradually slid outwardly of the head 27, and when the latter reaches the open inner end of the grease gun cylinder 28, the operation of the pump is discontinued. The valve 34 then closes so as to prevent dripping of grease from the spout 26 when the grease gun cylinder is entirely removed from the piston head 27. It will thus be seen that the grease gun cylinder may be effectively filled in an easy and expeditious manner without spilling the grease. It will be noted that when the grease initially enters the cylinder 28 of the grease gun, the valve 33 permits escape of air that may be trapped in said cylinder 28 outwardly or in front of the piston head 27. This can be effected by restraining movement of the cylinder 28 outwardly with respect to the piston head 27 until the trapped air has been discharged. As the cup packing 29 faces outwardly, it effectively prevents leakage of the grease inwardly

past the piston head 27 during the operation of filling the cylinder 28 of the grease gun.

From the foregoing description, it is believed that the construction and operation, as well as the advantages of the present invention, will be readily understood and appreciated by those skilled in the art. In handling certain heavy greases, it is possible to eliminate the check valve 33 and simply have an opening through the piston head 31. Jam nut 32 secures the parts 29, 30 and 31 in position with their openings in registry.

What I claim as new is:

1. In a grease dispensing pump, a discharge spout having an outlet end provided with a piston head adapted to slidably fit in the cylinder of a grease gun and including an outwardly facing cup packing, and means to forcibly discharge the grease through said spout so as to cause movement of the cylinder of the grease gun outwardly with respect to said piston head as said cylinder becomes filled with grease, said piston head having an air escape opening therethrough constantly permitting passage of air from the grease gun cylinder to the atmosphere as said air is displaced by the grease discharged into said cylinder from said spout.

2. In a grease dispensing pump for grease drums, a vertical pump cylinder having a top outlet provided with a downwardly and outwardly extending valved discharge spout, and a piston head on the lower end of said discharge spout arranged to slidably fit in the cylinder of a grease gun, said piston head having a cup packing arranged to be expanded by pressure of the grease entering the grease gun cylinder from the spout and thereby prevent leakage of grease outwardly between said piston head and said grease gun cylinder, the valve of said discharge spout opening outwardly and being spring-seated.

WALTER D. LYNCH.
